(57) **CLAIM**

The ornamental design for a formed potato product, as shown and described.

DESCRIPTION

FIG. 1 is a perspective view of a formed potato product showing my new design;

FIG. 2 is a top plan view thereof, the bottom plan view being a mirror image thereof; and,

FIG. 3 is a left side elevation view thereof, the front, back and right side elevation views being identical thereto.

1 Claim, 1 Drawing Sheet

FIG. 1

FIG. 2

FIG. 3
